UNITED STATES PATENT OFFICE.

GUSTAV A. FRIESS, OF CHICAGO, ILLINOIS.

SHEET-GRIPPING MECHANISM FOR PRINTING-PRESSES.

1,293,749.

Specification of Letters Patent. Patented Feb. 11, 1919.

Application filed February 12, 1916. Serial No. 77,839.

To all whom it may concern:

Be it known that I, GUSTAV A. FRIESS, subject of the Emperor of Germany, residing at Chicago, in the county of Cook and 5 State of Illinois, have invented certain new and useful Improvements in Sheet-Gripping Mechanism for Printing-PresSES; and I do hereby declare the following to be a full, clear, and exact description of the invention, 10 such as will enable others skilled in the art to which it appertains to make and use the same.

This invention has for its object to provide novel sheet-gripping means for the tympan 15 cylinders of printing presses, and has for its particular object to provide coacting sheet grippers which will grip the sheet at a point beyond the face of the impression cylinder, and will then automatically recede to a point 20 below such surface so as to present no projecting portions which may contact with and injure the printing cylinder of the press.

A further object of the invention is to provide sheet-gripping means of the character defined which, by reason of their projection beyond the surface of the cylinder, 25 are better positioned to receive the sheets to be printed for the purpose of feeding the same to the printing face of the printing 30 cylinder.

The invention consists in the features of construction and combination of parts hereinafter fully described and particularly claimed.

35 In the accompanying drawings illustrating a preferred embodiment of the invention:

Figure 1 is a fragmentary radial longitudinal section through the tympan cylinder of a printing press and a portion of the 40 frame thereof equipped with sheet-gripping mechanism embodying my invention.

Figs. 2, 3 and 4 are fragmentary detail transverse sections through the tympan cylinder and sheet-gripping mechanism 45 showing the latter in three different positions during the rotation of the tympan cylinder through an arc equal substantially to the angle between the radii of Figs. 2 and 4.

50 Fig. 5 is a fragmentary detail section through a portion of the frame showing a cam and a portion of gripper-operating mechanism for actuating the sheet-gripping means.

55 Figs. 6 and 7 are fragmentary detail transverse sections through the tympan cylinder

showing a portion of the sheet-gripping mechanism in two different positions.

Fig. 8 is a fragmentary detail end elevation of a portion of the tympan cylinder showing in section a projection for actuating 60 the sheet-gripping means.

Referring now to said drawings, A indicates the tympan or impression cylinder of a printing press which is provided contiguous to its ends with radial recesses B in 65 which guide blocks C are radially movable. The said guide blocks are integral with and disposed at the ends of an anvil bar D constituting a portion of the sheet-gripping means, both said blocks and said anvil members being normally held at the outer limit of their radial movement by means of the compression springs E bearing on the inner faces thereof. Suitable stops F are provided for limiting the outward movement 75 of the blocks C, said springs E being adapted to normally hold said blocks in engagement with said stops.

A shaft G is journaled at its ends in said blocks C, and is equipped between its ends 80 with a plurality of gripper fingers H, the hubs I of which are rigid with the said shaft G. Contiguous to the bearings for said shaft G the latter is provided with a pair of arms J in the outer ends of which 85 the heads K are pivotally secured. The guide recesses B of the cylinder communicate with the longitudinal recess or pocket L extending the entire length of the cylinder A, said gripper fingers and said arms J 90 being adapted to project or extend into said groove or recess L. On the longitudinal wall of the said recess L farthest removed from the nearest adjacent side wall of the grooves B there are mounted projections M 95 provided with pivoted heads similar to the heads K, and between said heads K and M helical compression springs O are interposed, said springs O being adapted to throw the shaft G to either of two positions, toward which it is primarily turned by means of the throw-over member P on 100 said shaft G and the pins or projections Q and R on the press frame.

Each of said blocks C carries an anti-friction roller S in the path of which are cam-surfaces T on the projections U of the press frame, said cam surfaces being disposed to effect an inward or depressing movement of the blocks C as said portion 105 of the cylinder A containing said gripper 110

mechanism approaches the surface of the printing cylinder N, and maintaining said blocks depressed until said portion of said cylinder A has passed the opposed portion 5 of said cylinder N.

The said projections U constitute inverted channels, the lower edges of the inner flanges of which are provided with said cam surfaces T and the inner face of the other 10 flange of one of which carries the two pins or projections Q and R, respectively, which extend toward the inner flange of said channel. The throw-over arm P on the shaft G is a channeled member and said pins or 15 projections Q and R are adapted to enter opposite ends of the same, being disposed in the paths of the opposite mouths of said channel for engaging in the same in the usual and well-known manner to turn said shaft G through arcs of a length sufficient to cause the springs O to throw said shaft through the balance of the arc requisite to effect engagement of the sheet between the gripper fingers H and the anvil member D, 20 and to throw said gripper fingers to the position shown in Fig. 4 and there hold the same while the cylinder A rotates through its longer arc. Thus the gripper mechanism is actuated at regular intervals 25 in the usual well-known manner but is moved bodily by independently operative mecha- 30

nism from its outer to its inner position and back while engaged with a sheet.

I claim as my invention:

In a printing press, a tympan cylinder 35 equipped with a sheet gripping mechanism, comprising an anvil member carried by the cylinder and arranged for radial movement relatively to the cylinder, anti-friction rollers rotatably mounted on the ends of the 40 anvil member, internal stationary cam surfaces on the press frame in the paths of said rollers and adapted to force the anvil member inwardly, compression springs beneath the ends of the anvil member normally 45 tending to hold the anvil member at the outer limit of its movement and a shaft mounted in bearings in the ends of the anvil member and movable therewith, gripper fingers for coöperation with the anvil member carried by said shaft, and means for 50 yieldingly holding the gripper fingers in contact with the anvil member as the same is moved radially.

In testimony whereof I have signed my name in presence of two subscribing witnesses.

GUSTAV A. FRIESS.
